UNITED STATES PATENT OFFICE.

JOHN HOFMANN, JR., OF STEARLEYVILLE, ASSIGNOR OF ONE-HALF TO
W. H. FUNK, OF BOWLING GREEN, INDIANA.

BRAKE FOR HAY-WAGONS.

SPECIFICATION forming part of Letters Patent No. 552,708, dated January 7, 1896.

Application filed November 30, 1894. Serial No. 530,443. (No model.)

To all whom it may concern:

Be it known that I, JOHN HOFMANN, Jr., a citizen of the United States, residing at Stearleyville, in the county of Clay and State of Indiana, have invented a new and useful 5 Brake for Hay-Wagons, of which the following is a specification.

The invention relates to improvements in brakes for hay-wagons.

10 The object of the present invention is to provide a simple and inexpensive brake, adapted to be readily applied to hay wagons or racks, and capable of enabling the front standard of a hay rack or wagon to be readily 15 folded without interfering with it, and adapted to be operated when the standard is in an upright position or is folded upon the frame or body.

10 The invention consists in the construction 20 and novel combination and arrangement of parts hereinafter fully described, illustrated in the accompanying drawings, and pointed out in the claim hereto appended.

25 In the drawings, Figure 1 is a perspective view of a hay-rack provided with my improvements. Fig. 2 is a longitudinal sectional view. Fig. 3 is a transverse sectional view. Fig. 4 is a detail view of the ratchet device.

30 Like numerals of reference indicate corresponding parts in all the figures of the drawings.

1 designates a hay rack or frame of a hay-wagon, of any suitable construction, and provided at its front with a hinged standard 2, 35 designed to support the front end of a ridge-pole. (Not shown.) The standard is composed of converging sides 3, and upper transverse pieces 4 and 5, arranged at different heights and adapted to receive the front end 40 of a ridge-pole, in order that a load of hay may be compactly secured upon the hay-rack, to enable the same to be safely carried over rough roads.

45 The front standard 2 is hingedly connected with the frame of the hay-rack by a transverse rock-shaft 6, journaled in suitable bearings of the side beams or sills 7, and forming a pintle for the front standard and provided adjacent to the inner face of one of them with 50 an arm 8, which is connected by rods 9 and 10 with a suitable brake-beam. The rock-

shaft has fixed to it a gear-wheel 11, which meshes with a bevel pinion 12, fixed to the lower end of an operating-shaft 13. The operating-shaft 13 extends longitudinally of the 55 front standard, and is journaled in suitable bearings of a lower cross-bar 14 and the top-most transverse bar 4, and it is connected by the beveled gear-wheels with the rock-shaft. It is provided at its upper end with a hand-wheel 15, and is retained at any desired adjustment, to maintain the brake applied to the 60 wheels by a ratchet-wheel 16, fixed to the shaft 13 and located at the top of the standard, and a pawl 17, pivoted to the transverse piece 4 65 and engaging the ratchet-wheel, and maintained in such engagement by a spring 18, secured to one of the sides of the standard. The pawl is provided intermediate of its ends and has one portion engaging the ratchet-wheel, and its other portion forms a handle. The spring has one end bearing against the 70 engaging end of the pawl, and it has considerable length and is provided intermediate of its ends with a curved portion or bend, as 75 clearly illustrated in Fig. 4 of the accompanying drawings, and the pawl is adapted to swing around out of engagement with the ratchet-wheel, where it will be held by the curved portion of the spring. This arrangement of 80 gear-wheels permits the front standard 2 to be swung upward for use or folded down upon the hay-rack without operating the brake, either to apply or release the same, and it also enables the brake to be applied, whether the 85 standard be folded or be in its operative position or at any intermediate point.

The gear-wheels are protected from becoming clogged by hay or the like by casing or shield 19, which is curved and which has its 90 upper end secured to the transverse bar 14, and which is secured at its lower end to a depending bar 20. The bar 20 forms a bearing for the rock-shaft, and is secured to the transverse bar 14 and to the adjacent side of the 95 standard.

It will be seen that the brake mechanism is simple and exceedingly inexpensive in construction, that it is adapted to be applied to any ordinary construction of hay-rack, and 100 that the rock-shaft, besides serving as the means for communicating motion from the

operating-shaft to the operated rods 9 and 10, also serves as efficient means for hinging the front standard to the frame of the hay-rack.

The operating-rod 10 is mounted in suitable guides, and may be connected with any ordinary form of brake-beam or brake-levers requiring a straight forward draft to produce an application of the brake-shoes.

Changes in the form, proportion, and the minor details of construction may be resorted to without departing from the principle or sacrificing any of the advantages of this invention.

What I claim is—

15 The combination with a frame, a transverse shaft 6 arranged horizontally and extending entirely across the frame and having its ends journaled at opposite sides thereof and provided at one end with an arm designed to be 20 connected with the brake mechanism, a standard provided at its bottom with bearings and receiving the shaft 6 therein and hinged by the latter to the frame, whereby the shaft performs the double function of a shaft and a 25 pintle, a vertically disposed beveled gear wheel fixed to the shaft 6, the shaft 13 extending longitudinally of the standard and journaled thereon and provided at its lower end

with a beveled pinion arranged at right angles to the gear wheel and meshing with the same and adapted to revolve freely and automatically around the gear wheel when the standard is swung upward or downward, a curved shield or casing fixed to the bottom of the standard and movable with the same and receiving the gear wheel, a ratchet wheel located at the top of the standard and fixed to the shaft 13, a pawl pivoted intermediate of its ends to the standard and having one end engaging the ratchet wheel and having its other end forming a handle, and a spring secured at one end to the standard and having its other end bearing against the engaging end of the pawl and provided intermediate of its ends with a curved portion and adapted to 45 permit the pawl to be swung around so as to hold it out of engagement with the ratchet wheel, substantially as described.

In testimony that I claim the foregoing as my own I have hereto affixed my signature in 50 the presence of two witnesses.

JOHN HOFMANN, JR.
